POWER-SHOVEL.

1,163,634.

Specification of Letters Patent. Patented Dec. 14, 1915.

Application filed July 23, 1914. Serial No. 852,573.

To all whom it may concern:

Be it known that I, EDWIN J. ARMSTRONG, a citizen of the United States, residing at Erie, in the county of Erie and State of Pennsylvania, have invented new and useful Improvements in Power-Shovels, of which the following is a specification.

This invention relates to power shovels and consists in certain improvements in the construction thereof as will be hereinafter fully described and pointed out in the claims.

More particularly the invention relates to improvements in power shovels whereby the cutting lip of the dipper may be made to travel in a pre-determined line so as to finish the grade at the completion of the excavation either as a plane surface or a grade having some pitch as for an ordinary road-way.

The invention is illustrated in the accompanying drawings as follows:

Figure 1 shows a side elevation of the machine. Fig. 2 a section on the line 2—2 in Figs. 1 and 3. Fig. 3 an enlarged view of the dipper stick and actuating mechanism.

1 marks the carriage, 2 the turn table and 3 the boom. The boom is supported by the usual stay 4 extending to the base 5 and the stays 6 returning to the turn table 2. These are of ordinary construction.

The dipper 7 is carried by the dipper stick 8. It has a cutting lip 9. The dipper stick is provided with the racks 10 engaging the gears 11. The gears 11 are carried by a shaft 12. The shaft 12 is mounted in boxes 12^a carried by the boom 3. A yoke 13 is pivotally mounted on the shaft 12 and forms a sliding connection in which the dipper stick 8 is mounted, the dipper stick swinging pivotally with the shaft 12 as a center, the yoke swinging with it and the stick sliding in the yoke as the gears 11 operate the racks 10. The shaft 12 is driven by a gear 14, the gear 14 meshing a gear 15. The gear 15 is driven directly by the engine 16. The engine is provided with the ordinary controlling mechanism 17 whereby the gear 15 may be rotated in either direction or stopped at any point. A link 18 leads from the controlling mechanism 17 to an adjusting lever 18^a. The adjusting lever is carried by a hand lever 19 and swings with it so that by operating the hand lever, the controlling lever or mechanism 17 may be actuated.

These mechanisms with the exception of the adjusting lever 18^a are of common construction. A pulley block 20 is secured to the dipper and a cable 21 runs from this block over a block 22 back to the hoisting engine 23 on the turn table. The dipper is swung or given pivotal movement by the action of the cable 21 and is operated in the sliding connection or given sliding movement by the action of the gears 11 on the racks 10.

It will be observed that while an operator could within limits by manual operation of the control 17 so control the sliding movement of the dipper stick 8 as to make the cutting lip 9 follow some desired path it will be understood that this movement of the dipper stick must be synchronous with the swinging movement under the influence of the cable 21 and must vary in extent with different portions of the travel of the dipper.

If no sliding movement were given to the dipper stick the cutting lip would describe an arc of a circle with the axis of the shaft 12 as a center. I prefer to limit the movement of the lip 9 to a pre-determined line, and to leave the controlling mechanism free to operate to lift the lip should rocks be encountered or should the work require the lifting of the dipper prior to the full sweep of the stick. I provide a mechanism which will automatically actuate the controlling mechanism to control the engine 16 so as to make the dipper stick follow a pre-determined line provided pressure is exerted on the operating lever so as to follow this automatic mechanism.

A rack 24 is mounted in a guide 25, the guide 25 being carried by the yoke 13 so that the guide 25 swings with the dipper stick 8. The rack 24 meshes with a gear 26 on the shaft 12. This gear 26 is preferably smaller than the gear 11 so that while the travel of the rack 24 is proportional at all times to the travel of the dipper stick yet it is very much less. The end of the rack engages a cam lever 27. This cam lever is pivoted at 27^a on the engine frame. A link 28 connects the cam lever 27 with the adjusting lever 18^a. It will be readily seen that if the hand lever 19 is forced forward the cam lever 27 will be forced forward into contact with the end of the rack 24 and that if pressure is exerted on the hand lever 19, the cam lever 27 will be kept in contact with the end of the rack 24. The surface of the cam lever is so formed with relation to the

travel of the rack 24 that the controlling mechanism 17 will be brought to neutral only with a position of the cutting lip 9 somewhere in the pre-determined line A. It will be understood that the controlling mechanism 17 when at neutral will bring the engine to a stop but that with the controlling mechanism in either direction from neutral the engine will be driven in one or the other direction, in one direction lifting the dipper and in the reverse direction lowering the dipper. This is a common construction of these mechanisms. To more readily understand the operation of the automatic control let us assume that the point of the dipper is above the line A. The small rack 24 will then be toward the right of the neutral position, thus allowing the cam lever 27 if it is held in contact with the end 20 of the rack 24 to be to the right. The controlling lever 19 which is ordinarily grasped by the operator will also be to the right and the controlling mechanism 17 will be to the right. The controlling mechanism 17 ordinarily is such that with a forward movement (toward the right) of the lever 19, the dipper is depressed. Consequently with the cam lever 27 toward the right of the neutral position and the lever 19 toward the right of the neutral position of the engine steam will be on the engine and the engine will be traveling to lower the dipper stick. As the dipper is lowered so as to approach the line A, the gear 26 is rotated thus moving the rack 24 toward the left and as the rack 24 is moved toward the left, it forces the cam lever 27 toward the left and this in turn through the links and levers forces the controlling mechanism toward the neutral position and this will continue until the controlling mechanism 17 reaches the neutral position when the engine will come to a stop. The cam lever is so shaped that this position will be reached with the point 9 at the line A, and this neutral position will be reached with the point 9 at the line A regardless of where the dipper is along the line A. This will be just as true with the dipper in the position shown in dotted lines 50 in Fig. 1 as in the position shown in solid lines. On the other hand if the point of the dipper should be below the line A this would have forced the cam lever to the left of the neutral position and this would have put the engine in motion to lift the dipper stick. If, however, the operator exerts pressure on the lever 19 so that the cam lever 27 follows the rack 24 in its movement toward the right, the controlling mechanism 17 will be moved toward neutral position with this upward movement of the dipper and will reach the neutral position when the dipper reaches the line A. It will be understood that in the normal operation of the machine, however, 60 there is no distinct succession of movements.

The dipper is lowered to its working position and is stopped at the neutral position automatically by the action of the rack 24 on the cam lever 27 and through the connecting links on the controlling mechanism. If the operator then exerts pressure on the lever 19, the engine will go faster or slower depending on how great a departure from the neutral position the levers are and in this way the engine will maintain the point 9 approximately along the line A. The engine cannot be at rest with the dipper away from this point because the controlling mechanism is forced away from neutral by a position of the dipper stick away from this line. This automatic control of the line of travel of the dipper not only accomplishes the finishing of the grade by the action of the dipper but also adds very much to the speed at which the shovel may be operated where excavation alone is desired because the operator in lowering the dipper to work can lower it at full speed and depend on the automatically controlled mechanism to retard and stop the dipper when properly lowered. This retarding and stopping of the dipper is accomplished without shock or jar because it is done by the engine itself, the steam forming a cushion for stopping the movement. This is true because if the dipper tends to go beyond the line determined for the lower line, as A, the engine is reversed and the dipper moves directly against the driving power of the engine so that if there is any tendency to over-run the engine catches it and returns the dipper to the pre-determined position. In the normal operation, however, there is no material over-running because as soon as the dipper stick has dropped far enough to bring the cutting lip 9 to this pre-determined line a rearward action of the rack 24 will have forced the lever 27 toward the rear sufficiently to bring the controlling mechanism 17 to neutral. At all times, however, the hand lever 19 may be pulled back or toward the left as shown in Fig. 1 so as to lift the dipper stick as desired.

I prefer to provide the adjusting lever 18^a. This has a latch 30 which engages the catches 31 on a quadrant 32 extending from the hand lever 19. By changing the adjustment of the lever 18^a the position of the cam lever 27 which will bring the controlling mechanism 17 to neutral is varied so that the predetermined line will vary from a horizontal line and thus if the sweep of the dipper is toward the sides of the machine a pitch may be given to the grade as for instance the pitch of an ordinary road-way. This may be varied by varying the position of the adjusting lever 18^a. The shape of the lever may be readily determined by laying out the point 9 at different points along the desired grade line and then plotting the 110 115 120 125 130

point assumed by the end of the rack 24. This will give the shape of the lever 27.

What I claim as new is:—

1. In a power shovel, the combination of 5 a boom; a dipper having a cutting lip; a dipper stick on which the dipper is mounted having a pivotal and sliding connection with the boom; mechanism for swinging the dipper on the pivotal connection; a rotating device 10 imparting a sliding movement to the stick on the sliding connection synchronously with the pivotal movement; a motor for actuating said device; and means controlling the motor and actuated by the device 15 for limiting the movement of the lip of the dipper to a predetermined line involving a synchronous swinging and sliding movement of the dipper stick.

2. In a power shovel, the combination of 20 a boom; a dipper having a cutting lip; a dipper stick on which the dipper is mounted having a pivotal and sliding connection with the boom; mechanism for swinging the dipper on the pivotal connection; a rotating device 25 imparting a sliding movement to the stick on the sliding connection synchronously with the pivotal movement; a motor for actuating said device; and means controlling the motor and actuated by the device 30 for limiting the movement of the lip of the dipper to a predetermined line involving a synchronous swinging and sliding movement of the dipper stick, said means being free for manual operation to move the dipper stick in one direction to control the dipper stick at points above said line.

3. In a power shovel, the combination of 40 a boom; a dipper having a cutting lip; a dipper stick on which the dipper is mounted having a pivotal and sliding connection with the boom; mechanism for swinging the dipper on the pivotal connection; a rotating device 45 imparting a sliding movement to the stick and the sliding connection synchronously with the pivotal movement; a motor for actuating said device; means controlling the motor and actuated by the device for limiting the movement of the lip of the dipper to a predetermined line involving a synchronous swinging and sliding movement of the dipper stick; and apparatus for varying and controlling the means to vary the line through which the dipper lip moves.

4. In a power shovel, the combination of 55 a boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving gear is mounted, the axis of the shaft being the axis of the pivotal connection of the stick with the boom; a motor for actuating said 60 driving gear; a controlling means for the

motor; a controlling gear on the shaft; a controlling rack slidably mounted to swing with the stick and meshing the controlling gear; and devices actuated by the controlling rack and acting on said means to control the motor to limit the movement of the lip of the dipper to a predetermined line involving a synchronous pivotal and sliding movement of the stick.

5. In a power shovel, the combination of 75 a boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving gear is mounted; the axis of the shaft being the axis of the pivotal connection of the stick with the boom; a motor for actuating said 80 driving gear; a controlling means for the motor; a controlling gear on the shaft; a controlling rack slidably mounted to swing with the stick and meshing the controlling gear; and devices actuated by the controlling rack and acting on said means to control the motor to limit the movement of the lip of the dipper to a predetermined line involving a synchronous pivotal and sliding movement of the stick, said means being free 85 for manual operation to move the dipper stick in one direction to control the dipper stick at points above said line.

6. In a power shovel, the combination of a 100 boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving gear is mounted, the axis of the shaft being the axis of the pivotal connection of the stick with the boom; a motor for actuating said 105 driving gear; a controlling means for the motor; a controlling gear on the shaft; a controlling rack slidably mounted to swing with the stick and meshing the controlling gear; devices actuated by the controlling rack and acting on said means to control the motor to limit the movement of the lip of the dipper to a predetermined line involving a synchronous pivotal and sliding movement of the stick; and apparatus 110 for varying and controlling the means to vary the line through which the dipper lip moves.

7. In a power shovel, the combination of a 115 boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving 120 gear is mounted, the axis of the shaft being the axis of the pivotal connection of the stick with the boom; a motor for actuating said driving gear; a controlling means for the 125

driving gear; a controlling gear on the shaft; a controlling rack slidably mounted to swing with the stick and meshing the controlling gear; and devices actuated by the controlling rack and acting on said means to control the motor to limit the movement of the lip of the dipper to a predetermined line involving a synchronous pivotal and sliding movement of the stick; and apparatus for varying and controlling the means to vary the line through which the dipper lip moves.

gear is mounted, the axis of the shaft being the axis of the pivotal connection of the stick with the boom; a motor for actuating said driving gear; a controlling means for the motor; a controlling gear on the shaft; a controlling rack slidably mounted to swing with the stick and meshing the controlling gear; and devices actuated by the controlling rack and acting on said means to control the motor to limit the movement of the lip of the dipper to a predetermined line involving a synchronous pivotal and sliding movement of the stick, said devices comprising a cam lever on which the controlling rack operates; a hand lever connected with the cam lever; and a connection between the hand lever and said means.

8. In a power shovel, the combination of a boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving gear is mounted, the axis of the shaft being the axis of the pivotal connection of the stick with the boom; a motor for actuating said driving gear; a controlling means for the motor; a controlling gear on the shaft; a controlling rack slidably mounted to swing with the stick and meshing the controlling gear; and devices actuated by the controlling rack and acting on said means to control the motor to limit the movement of the lip of the dipper to a predetermined line involving a synchronous pivotal and sliding movement of the stick, said devices comprising a cam lever on which the controlling rack operates; a hand lever connected with the cam lever; a connection between the hand lever and said means, and means for adjusting one of said connections to vary the predetermined line to which the travel of the lip of the dipper is limited.

9. In a power shovel, the combination of a boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving gear is mounted, the axis of the shaft being the axis of the pivotal connection of the stick with the boom; a motor for actuating said driving gear; a controlling means for the motor; a controlling gear on the shaft; a controlling rack slidably mounted to swing with the stick and meshing the controlling gear; devices actuated by the controlling rack and acting on said means to control the dipper stick in one direction to control the dipper stick at points above said line.

9. In a power shovel, the combination of a boom; a dipper having a cutting lip; a dipper stick on which the dipper is mounted having a pivotal and sliding connection with the boom; mechanism for swinging the dipper on the pivotal connection; a rack on the dipper stick; a driving gear meshing with the rack; a shaft on which the driving gear is mounted, the axis of the shaft being the axis of the pivotal connection of the stick with the boom; a motor for actuating said driving gear; a controlling means for the motor; a controlling gear on the shaft; a controlling rack slidably mounted to swing with the stick and meshing the controlling gear; devices actuated by the controlling rack and acting on said means to control the motor to limit the movement of the lip of the dipper to a predetermined line involving a synchronous pivotal and sliding movement of the stick, said devices comprising a cam lever on which the controlling rack operates; a hand lever connected with the cam lever; a connection between the hand lever and said means, and means for adjusting one of said connections to vary the predetermined line to which the travel of the lip of the dipper is limited.

In testimony whereof I have hereunto set my hand in the presence of two subscribing witnesses.

EDWIN J. ARMSTRONG.
